UNITED STATES PATENT OFFICE.

GEORGE BROWNLEE, OF PRINCETON, INDIANA.

IMPROVEMENT IN LAMPS.

Specification forming part of Letters Patent No. **138,070**, dated April 22, 1873; application filed February 8, 1873.

To all whom it may concern:

Be it known that I, GEORGE BROWNLEE, of Princeton, in the county of Gibson and State of Indiana, have invented a new and Improved Safety-Burner; and I do hereby declare that the following is a full, clear, and exact description of the same, reference being had to the accompanying drawing forming a part of this specification, in which—

Figure 1 is a vertical section of my safety-burner on the line *c c*, Fig. 2. Fig. 2 is a top view of the same with dome and chimney-carrier taken off. Fig. 3 is a detail vertical transverse section on line *x x*, Fig. 2. Fig. 4 is a detail side view, partly in section, showing notches and rest for sliding lever. Fig. 5 is a horizontal section of the dome on line *y y*, Fig. 1; and Fig. 6 is a vertical section of the dome, showing shape thereof.

Similar letters of reference indicate corresponding parts.

The object of my invention is to construct a burner for coal-oil lamps by the use of which explosions may be prevented, a quick extinguishment of the flame be obtained, and clearer and brighter light be produced. My invention consists in a weighted valve on the end of a lever connected with a tubular wick-slide, which extinguishes the flame either by the pressure of the oil-gases or at will by jerking the lamp or inclining the same.

In the drawing, *A* represents the body of the lamp, with a handle, *B*. To the body *A* is applied in the usual manner the burner with wick-tube and dome. An aperture, *b*, in the bottom of the burner leads to a second bottom, *d*, with a corresponding aperture, into which is placed the extension *e* of an L-shaped weighted valve, Fig. 1. The lever-arm of valve *C* rests on plate *d*, and is pivoted at *s* between the wick-tube and outer casing, so as to swing freely therein. An upward extension, *g*, of the arm of valve *C* forms with a movable lug, *h*, a small recess for spring *D*. The spring *D* is made of wire applied to the inside of the metallic casing, and bent so as to pass through the recess between extension *g* and lug *h*. It then passes to the outside of the perforated casing *E*, which has notches *i*, between which said spring is moved up and

down. A projection, *K*, at the lower notch, holds spring *D* therein until the latter is displaced. The spring *D* is further attached to suitable projections *l* of a tube, *F*, fitted over the wick-tube, and sliding up and down thereon. By a screw and nut, *G*, connected by a wire, *m*, to lever *D*, the action of the same is regulated at pleasure. A perforated plate, *n*, covers the valve and extinguisher mechanism, and allows a steady supply of air to the flame. The spring *D* is pressed down into the lower notch *i* under the projection *K*, and the regulator *m* is so adjusted by nut *G* that the least pressure will disconnect spring *D* from the lower notch and carry the sliding tube *F* over the wick-tube.

The oil-gases developed in body *A*, pressing on extension *e* of weighted valve *C*, will lift the same, and with it the pivoted end pin *g*, so that spring *D* is released and tube *F* made to slide upward over the wick, extinguishing the flame. The same effect will be produced by inclining the body of the lamp or jerking the same.

By these means a great number of accidents, arising partly from impure oil or the careless handling of the lamp, may be altogether avoided.

H is the chimney-plate with a series of perforations, *O*, with outside indentations *r*, slot *p*, and rounded projections *q*.

Having thus described my invention, what I claim as new, and desire to secure by Letters Patent, is—

1. A weighted valve, *C*, having the extension *e* applied to an aperture in the plate *d* over the body *A*, as and for the purpose described.
2. The lever-arm of valve *C*, having upward projection *g* and lug *h*, combined with the spring *D* and notch *K* of casing, as described, to form a connection between valve *C* and sliding extinguisher *F*, as and for the purpose set forth.
3. The screw-regulator *G m* applied to the spring *D*, as and for the purpose specified.

GEORGE BROWNLEE.
